(57) **CLAIM**

The ornamental design for a single-use, disposable container, as shown and described.

DESCRIPTION

FIG. 1 is a top, front perspective view of a single-use, disposable container showing the claimed design;
FIG. 2 is a bottom, front perspective view thereof;
FIG. 3 is a front elevation view thereof;
FIG. 4 is a rear elevation view thereof;
FIG. 5 is a left-side elevation view thereof;
FIG. 6 is a right-side elevation view thereof;
FIG. 7 is a top view thereof;
FIG. 8 is a bottom view thereof;
FIG. 9 is a partial enlarged view according to broken circle “9” shown in FIG. 1; and,
FIG. 10 is a partial enlarged view according to broken circle “10” shown in FIG. 2.

The broken lines of even length shown represent the boundaries of the partial enlarged views and form no part of the claimed design.
